UNITED STATES PATENT OFFICE

2,003,266

CONTROL FOR RAILWAY SIGNAL SYSTEMS

Frank H. Richterkessing, Louisville, Ky., assignor to Nachod & United States Signal Co., Inc., Louisville, Ky., a corporation of New York

Application February 1, 1932, Serial No. 590,245

27 Claims. (Cl. 246—58)

My invention relates to improvements in controls for railway signal systems especially those adapted to control car or train movements upon a railway, and more particularly upon an electric railway, and is an improvement upon the disclosure in United States application for Letters Patent Ser. No. 587,687, filed January 20th, 1932.

The main object of my invention is to provide a control in which the moving train is adapted to 10 automatically close the electric control circuits through the axle and wheels thereof, although the control system may be operated by other contacting devices such as trolley contactors, in which the current collector of the vehicle is 15 adapted to contact therewith, or through track instruments which may be actuated by depression of the running rails or by mechanical or electrical engagement with the wheels of the train.

20 A further object of my invention is to provide a system in which failures in the circuits or apparatus will render the control inoperative to perform an improper operation, thereby providing a minimum of danger to the traffic operating thereon.

25 A still further object of my invention is to provide a control which will not be operative through the breakdown of any of the insulated joints, and which is further arranged so that under such faulty conditions the control will be 30 rendered non-responsive to set or clear a signal.

35 A still further object of my invention is to produce a signal controlling apparatus of the character above referred to, in which an improper or uncontemplated actuation of the signal control relay will be prevented in the event a continuous circuit is not maintained through the successive engagement of the two contact members, as for instance, when short rail sections are employed, 40 or because of the presence of dirt, leaves or other insulating material on the track.

45 A still further object of my invention is to provide a control which will be ineffective to operate the signal control relay in the event any of the operating coils, connecting wires, contacts or insulation, become short circuited or open circuit- 50 ed. This control feature is highly desirable when applied to the control of an automatic crossing gate, since the failure of the apparatus will not retain the gate as a permanent barrier on the arterial highway.

55 My invention further consists of certain novel constructions and characteristics which are fully discussed in the following description and ac-

companying drawings in illustration thereof, in which—

Figure 1 is a diagrammatic drawing of my invention illustrating a control which is directional-sensitive and which will perform in the manner heretofore designated. 5

Fig. 2 is a modification of Figure 1 in which the control relays are equipped with a mechanical locking feature to mechanically retain the actuation of the signal control armature. 10

Fig. 3 is a further modification of Fig. 1 in which the relays are not employed to be directional-sensitive, and which are further illustrated as controlling a signal control relay of the mechanical interlocking type. 15

Fig. 4 is a still further modification of Fig. 1 in which the control is directional-sensitive and operable by a train moving in one direction only. 20

Fig. 5 is a modification of Fig. 4 in which the control relay is designated as the mechanical interlocking type. 20

Fig. 6 illustrates the embodiment of my invention as disclosed in Fig. 5 in a signaling system adapted to control car or train movements upon a railway. 25

Fig. 7 illustrates the embodiment of my invention disclosed in Fig. 1 as applied to a signaling system adapted to control car or train movements in both directions upon a railway.

With further reference to Fig 1, the characters 30 RR and RR¹ designate the running rails of a railway system, and it is obvious to those skilled in the art that the rails may be those of an electric railway system utilizing the rails as a conductor for the return propulsion current for the train 35 traveling thereon, or for trains which are operated by other methods.

It will be further obvious to those skilled in the art that the wires 1 and 5 connecting the short insulated rail sections X and X¹ may be connected 40 to any form of contacting device which may be successively operated by a moving train or moving vehicle of any nature. It will be further noted that the running rail RR¹ is provided with insulated rail joints of the conventional type, which 45 are designated by the numerals 27, 28 and 29 respectively. Connecting bond wires 25 and 26 are shown as connecting the running rails RR and RR¹, and it is obvious that these connections are not necessary for the operation of my invention 50 but are illustrated since it is customary in practice to make the installation in this manner so that both running rails may be employed for conducting the return propulsion current.

In the control apparatus I employ the trans- 55

former T for reducing the high line voltage to a comparatively low voltage for the operation of the track control relays. The transformer T is provided with a secondary S supplying the low voltage, and a primary P which is connected to the high voltage line. It is obvious to those skilled in the art that it is not necessary to employ a transformer for the operation of my invention, and that batteries or other sources of operating current could be substituted therefor. It is still further obvious that the alternating current output of the transformer could be rectified in any conventional manner so that direct current would be supplied for the control of the track control relays.

I also employ relays of the conventional type which are designated by the characters E, F, F' and E' respectively and each is provided with the conventional operating coil and armature for controlling the electrical circuits.

In Figs. 2, 3, 5, 6 and 7, the character L designates a mechanical locking type of relay, which embraces each of the operating coils C4 and C5. The two operating coils C4 and C5 are positioned in a definite relation to each other, and in such a manner that their armatures will operate a mechanical locking device LO positioned therebetween. When the operating coil C5 is energized and raises its armature AC5, the armature will be mechanically held in the raised position by the locking arm LO as illustrated in Fig. 2 and when the operating coil C4 is energized and raises its respective armature AC4, the locking arm LO will be moved out of locking engagement with the armature AC5, thereby permitting the latter armature to be brought into engagement with its respective back contact. It is believed that a further detailed discussion of the operation and the construction of this relay is unnecessary, since it will be obvious to those skilled in the art how such a relay may be constructed to perform in the manner designated. In each of the drawings accompanying the specification like numerals and characters have been employed to designate identical or similar parts. It is therefore believed that lengthy descriptions of each of the figures are unnecessary since the teachings of one description may be applied to the remaining figures.

With further reference to Fig. 1, it will be noted that the parts embracing the track circuit control are diagrammatically represented as being in their normal conditions. It will likewise be noted that the primary P of transformer T is permanently connected to the 110 volt A. C. service through connecting wires 18, 19 and 20. It will be further evident that since the secondary S of the transformer T is connected through wire 15 to the running rail RR1, the wheels of a moving train operating over the insulated sections X and XI will complete circuits from the wire 15 for the operation of the control system. Assuming that the wheels of the train first contact with the insulated section X, a circuit will be completed from wire 15, through the running rails, wheels and axles of the train to the insulated section X, through wire 1, armature AE of relay E, back contact 2 of relay E, wire 3, operating coil C1 of relay F, wire 4, which is the other power terminal of the secondary S of transformer T. Instant to the completion of this circuit the armature AF of relay F will be brought out of contact engagement with its back contact 6 and into contact engagement with its front contact 8, but no further change will take place in the control since a circuit has not been completed to the insulated section XI. As

the train advances and the front wheels of the train engage the insulated section XI and the rear wheels of the train remain in contact engagement with insulated section X, the same terminal of transformer secondary S will be applied to both wires 9 and 10 connecting operating coil C2 of relay F', therefore relay F' will be inoperative during this interval. This circuit is completed from wire 15, through the running rails, axles and wheels to the insulated section XI, through wire 5, armature AF of relay F, front contact 8 to wire 9, winding C2, wire 10, rails of X, wheels and axles of the train to 26 and to the same terminal of S from which the circuit started. The energizing circuit for winding C1 will remain established from wire 15, through the running rails, wheels and axles to the insulated section X, through wire 1, through armature AE and back contact 2 of relay E and will be maintained for retaining the armature AF of relay F in its raised position. As soon as the train advances and the rear wheels disengage the insulated section X the circuit connections leading to wire 10 will be changed and thereby a circuit will be established for the operating coil C2 of relay F'. The latter circuit is completed from wire 15, through the running rails, axles and wheels, through the insulated section XI, through wire 5, armature AF of relay F, wire 8, wire 9, operating coil C2 of relay F', wire 10, armature AE of relay E, back contact 2 of relay E, wire 3, operating coil C1 of relay F to wire 4, which is the other terminal of the secondary S of transformer T. It will be noted that the operating circuit for the operating coil C2 was completed through the operating coil C1, thereby retaining the armature AF of relay F in contact engagement with its front contact. It will be evident that the latter mentioned operation will result in the armature AF' of relay F' being brought into contact engagement with its front contact 21, and that a circuit will be established from the BX power terminal through wire 18, wire 16, wire 17, armature AF' of relay F', front contact 21, to wire 22, which may be utilized for controlling any type of signaling apparatus. It will further be obvious from the latter description that should the train engage the insulated section XI subsequently to the engagement of the insulated section X, the operating coil C of relay E will be first energized and that the operating coil C3 of the relay E' will be subsequently energized in the same manner as described for the relays F and F' respectively, and it is believed that since these circuits are symmetrical and identical in operation a description embracing these circuits is unnecessary.

From the foregoing description it can be noted that the system utilizes a very simple principle to gain the desired features as heretofore mentioned. The principle further resides in first operating a relay for selecting direction, then operating the relay for controlling the signal circuits in a stick circuit, and that the stick circuit can not be established unless the insulated sections are successively engaged and disengaged. It can therefore be noted that in the event a vehicle first engages the insulated section X, and then comes into full contact engagement with the insulated section XI as hereinbefore described, the train operates relays F' and F respectively, and should the circuit for operating coil C2 of relay F' become interrupted through the wheels being intermittently insulated from the insulated section XI by dirt, leaves, etc. both relays F and F' will release and upon

re-establishing a circuit connection with the insulated section X_1 through the wheels and axles of the train, the relay E will then be operated but the relay F_1 will not be affected. Neither will the relay E_1 be affected to perform a reverse controlling operation, since the relay E_1 can be operated only by a train first engaging insulated section X_1 , then engaging X_1 and X simultaneously, disengaging X_1 , and remaining in engagement with section X . It can be further noted that a breakdown of the insulated joint 28 will extend the sections X and X_1 into a single insulated section, which will not permit successive circuits to be established for the operation of relay E_1 or F_1 . It can be further noted that should either of the insulated joints 27 or 29 break down, the relays F_1 and E_1 will remain inoperative since the terminals of either operating coil C_2 or C_3 of relays F_1 and E_1 will be connected to the same terminal of transformer secondary S . As for instance, the breakdown of the insulated section 27 would complete a circuit for the operation of relay F , and connect terminal 15 of transformer secondary S to wire 10 , and when a vehicle traveled in either direction over the insulated sections and engaged the insulated section X_1 terminal 15 of transformer secondary S would be applied through armature AF , contact 8 to wire 5 , wire 9 , which would not affect the operating coil C_2 of relay F_1 since each of the coil terminals would be connected to the same transformer secondary terminal.

In Fig. 2 applicant has illustrated a mechanical interlocking relay L substituting for the neutral relays E_1 and F_1 employed in Fig. 1. It will be apparent to those familiar with the art that the circuit connections for the various relay operating coils of Fig. 2 are identical to those dealt with in Fig. 1.

In Fig. 2 the operating coils C_4 and C_5 correspond to operating coils C_2 and C_3 of Fig. 1 and each is energized in the same manner as hereinbefore described for Fig. 1. The operating coil C_4 is equipped with an armature AC_4 which corresponds to the armature AF_1 of relay F_1 in Fig. 1. The operating coil C_5 is likewise provided with an armature AC_5 which corresponds to armature AE_1 of relay E_1 in Fig. 1. Positioned between the armatures AC_4 and AC_5 is a mechanical interlocking device LO for retaining the armature AC_5 in a raised position after the operating coil C_5 has been momentarily energized. It will be apparent that the mechanical interlock LO will be removed from the armature AC_5 , when the armature AC_4 is operated through the energization of operating coil C_4 . Therefore, the armature AC_5 will remain in its released position until the operating coil C_5 is again energized.

In Fig. 3, applicant has illustrated his system shown in Fig. 1 controlling the same operating coil of an auxiliary relay when the contact sections X and X_1 are bridged in either direction by the wheels of a train. It will be noted that each of the relays F_1 and E_1 are respectively provided with armatures AF_1 and AE_1 which are identical to those illustrated in Fig. 1 for relays F_1 and E_1 . It will be further evident that instead of the front contacts 21 and 23 controlling separate circuits, they are connected through wire 22 and further connected to operating coil C_4 through wire 24 . The relay L , of Fig. 3 corresponds to the mechanical interlocking relay dealt with in Fig. 2. It will be apparent to those familiar with the art however that in Fig. 3 the operating coil C_4 is energized through a circuit

completed by either armature AE_1 of relay E_1 , or armature AF_1 of relay F_1 for attracting the armature AC_4 to release the mechanical interlocking device LO from the armature AC_5 . In Fig. 3 the operating coil C_5 , which attracts armature AC_5 , is energized through wire 32 from some remote point, which may be through a push button or auxiliary controlling apparatus at some other location.

In Fig. 4, applicant has illustrated his system, shown in Fig. 1 eliminating the relay E_1 . In making this change it will be noted that front contact 11 of relay E is connected through wire 12 to one coil terminal of operating coil C . In this manner the operating coil C of relay E is retained energized for a successive engagement of X_1 and X . When a train travels in the reverse direction, first engaging the insulated rail section X , then X_1 , the operating coils of relays F and F_1 are energized in the same manner as dealt with in Fig. 1. It will therefore be evident, that the modification of Fig. 1, illustrated in Fig. 4, provides a "unidirectional" system; that is, the relay F_1 is operative by a train moving in one direction.

In Fig. 5, applicant has illustrated the unidirectional feature embraced in Fig. 4 as being used in connection with the mechanical interlocking relay L dealt with in Fig. 2. It will be evident to those familiar with the art that the operating coil C_4 of relay L in Fig. 5 corresponds to the operating coil C_2 of relay F_1 in Fig. 4. When the operating coil C_4 is energized the armature AC_4 is attracted thereby removing the mechanical interlocking device LO from the armature AC_5 , resulting in the armature AC_5 mechanically moving to its released position. The armature AC_5 will remain in this position until the operating coil C_5 is energized through wire 32 from some remote point.

It is believed that the similarity between Figs. 1 to 5 inclusive will be apparent to those familiar with the art and that a further detailed description is unnecessary since their operation can be traced by referring to the description of Fig. 1. In each of the latter mentioned figures like numerals and characters have been employed to designate identical parts.

In Fig. 6, applicant has illustrated his signal system appearing in his co-pending United States application for Letters Patent, Ser. No. 587,687, filed January 20th, 1932, as employing the "unidirectional" system illustrated in Fig. 5 for controlling the signal controlling relay L .

In Fig. 7, he has similarly illustrated his co-pending United States application for Letters Patent, Ser. No. 587,687, filed January 20th, 1932 as employing the "directional-sensitive" system dealt with in Fig. 1. It will therefore be apparent to those familiar with the art that the introduction of the "directional-sensitive" control to the above mentioned application has rendered the control of the signal operative by a train moving in either direction, that is, when a train travels in the normal direction first entering block 1 , then block 2 , etc., the signals at the entrance of each block will be utilized to provide protection in the rear of the train to prevent cars from following closely behind a preceding car, but when the train travels in a direction reverse to normal, first engaging block 3 , then block 2 , etc., the signals at the entrance of each respective block will be utilized to provide facing protection for the car moving against the normal direction of traffic. The signal controlling re-

lays in Fig. 7 function in the same manner as the signal controlling relays in the co-pending application referred to above, however, the train controlled relays E, F, F' and E' are employed to selectively energize the operating coils of the signal controlling relay L, dependent upon the direction in which the train moves through the successive blocks. It will be further evident to those familiar in the art that the features introduced in Fig. 7 are desirable for service conditions, since often it is necessary to move a train through signaled territory in a direction reverse to the normal flow of traffic, in which case it would be desirable to utilize the signals to protect such movements. In applicant's co-pending application, Ser. No. 587,687, the "directional" feature is not employed since this desirable feature has been rendered possible through the development of the system shown in Fig. 1 of this application.

It is believed that since this application deals in detail with the "directional-sensitive" system, and the co-pending application deals in detail with the functions of the various signal controlling relays, a further detail description for Figs. 6 and 7 is unnecessary.

While I have been specific in the arrangement and application of the apparatus and circuits embracing my invention, it is to be expected that many modifications may be possible without departing from the spirit and principle of my invention. Therefore the object of my invention is not limited to any specific construction or particular arrangement of circuits or controlling contact devices except as embraced in the claims.

I claim:

1. An electrical control for railway signals, comprising, a track, one of the rails of said track comprising insulated sections to be bridged by the wheels of a car or train, a plurality of electro-magnets, connections between the said insulated sections and said electro-magnets whereby the wheels of a train engaging the said sections when moving in different directions will energize different electro-magnets, and means responsive to the energization of either of the latter said electro-magnets and the successive engagement of the wheels with the said sections for energizing one or another of a second group of electro-magnets dependent upon the order of the successive engagement of the said sections, and means for retaining the energization of the selected electro-magnet of the first said group during the successive engagement of the said sections.

2. An electrical control for railway signals, comprising, a track, one of the rails of the said track consisting of insulated sections, a relay, an operating coil having a circuit including an armature of the said relay and one of the said insulated sections; a second operating coil and a second circuit including another one of said insulated sections, an armature and front contact controlled by the first said operating coil, the armature of the said relay and the first said operating coil, another circuit including the said second insulated section, the armature controlled by the first said operating coil and an operating coil of the said relay, and a third operating coil having a circuit including the first said insulated section, the armature and a front contact of the said relay, the armature controlled by the first said operating coil and the operating coil of the said relay, the armature controlled by the first said operating coil and the operating coil of the said relay, whereby the successive engagement of the wheels of a car or train with the said insulated sections in either direction will energize one or the other of the said second and third operating coils and retain the energization of either the first said operating coil or the operating coil of the said relay, dependent upon the direction in which the moving vehicle is operating.

3. An electrical control for railway signals, comprising,

prising, a track, one of the rails of the said track consisting of insulated sections, a relay, an operating coil having a circuit including an armature of the said relay and one of the said insulated sections; a second operating coil and a second circuit including another one of said insulated sections, an armature and front contact controlled by the first said operating coil, another circuit including the said second insulated section, the armature controlled by the first said operating coil and an operating coil of the said relay, and a third operating coil having a circuit including the first said insulated section, the armature and a front contact of the said relay, the armature controlled by the first said operating coil and the operating coil of the said relay, whereby the successive engagement of the wheels of a car or train with the said insulated sections in either direction will energize one or the other of the said second and third operating coils.

4. An electrical control for railway signals comprising, a track, one of the rails of the said track consisting of insulated sections, a relay, an operating coil having a circuit including an armature of the said relay and one of the said insulated sections; a second operating coil and a second circuit including another one of said insulated sections, an armature and front contact controlled by the first said operating coil, another circuit including the said second insulated section, the armature controlled by the first said operating coil and the operating coil of the said relay, and a third operating coil having a circuit including the first said insulated section, the armature and a front contact of the said relay, the armature controlled by the first said operating coil and the operating coil of the said relay, whereby the successive engagement of the wheels of a car or train with the said insulated sections in either direction will energize one or the other of the said second and third operating coils and retain the energization of either the first said operating coil or the operating coil of the said relay, dependent upon the direction in which the moving vehicle is operating.

5. An electrical control for railway signals, comprising, a track, one of the rails of the said track consisting of insulated sections, a pair of electro-magnets, circuit connections between the said insulated sections and said electro-magnets adapted to control the selective energization of one or the other of said electro-magnets when trains move in different directions and engage the said insulated sections, and means affected by the energization of said electro-magnets to effect the selective operation of signal controlling means, the first said means affected by the permanent energization of one of said circuits to render the electro-magnets ineffective to effect the operation of the first mentioned means.

6. An electrical control for railway signals, comprising, a track, one of the rails of the said track consisting of insulated sections, a plurality of electro-magnets, circuit connections between the said insulated sections and said electro-magnets adapted to control the selective energization of one or the other of said electro-magnets to effect the selective operation of signal controlling means, the first said means affected by the permanent opening of any of the first mentioned circuit connections to render either electro-magnet completely ineffective to effect the operation of the signal controlling means.

7. An electrical control for railway signals, comprising, a track, one of the rails of the said

- track consisting of insulated sections, a plurality of electro-magnets, circuit connections between the said insulated sections and said electro-magnets adapted to control the selective energization 5 of one or the other of said electro-magnets when trains move in different directions and engage the said sections, and means affected by the energization of said electro-magnets to affect the selective operation of signal controlling means.
- 10 10. the first said means affected by an intermittent interruption in the successive bridging of the said sections to render the electro-magnets ineffective to effect the operation of the signal controlling means.
- 15 15. 8. In an electrical control for railway signals, comprising, in combination, a plurality of electro-magnets, circuits for controlling the selective energization of the said electro-magnets, train controlled means for energizing the said circuits 20 successively whereby a train moving in different directions will affect the said means and energize one or the other of said electro-magnets, and means affected by the energization of said electro-magnets to effect the operation of signal controlling means, the said circuits adapted to render the said electro-magnets ineffective to effect the operation of the second mentioned means when the said train controlled means fails to energize the said circuits successively.
- 25 30. 9. A signal controlling apparatus having, in combination, a pair of electro-magnets, a vehicle controlled circuit for each electro-magnet, each electro-magnet controlling the circuit of the other said electro-magnet whereby only one of 35 the said electro-magnets is energized when the said vehicle controlled circuits are successively energized in response to a vehicle moving in one direction, a signal activating means affected by the selective operation of one of the said electro- 40 magnets by one of said circuits and the subsequent energization of the other vehicle controlled circuit, and means for rendering the said signal controlling means ineffective upon interruption of the said subsequently energized vehicle controlled circuit.
- 45 50. 10. A circuit controller for railway signals, comprising a plurality of electro-magnets, vehicle controlled circuits to be successively energized in response to a moving vehicle, the said circuits adapted to effect the energization of one or 55 another of said electro-magnets dependent upon the direction of movement of the said vehicle, and means responsive to the energization of either of the latter said electro-magnets and the successive energization of the said vehicle controlled circuits, for selectively energizing one or the other of a second group of electro-magnets and retaining the energization of the active electro-magnet of the first mentioned group.
- 60 65. 11. A signal controlling apparatus having, in combination, a pair of electro-magnets, a circuit for each of the said electro-magnets energized in response to the movement of a vehicle, each said circuit adapted to effect the energization of one or the other of said electro-magnets dependent upon the direction of movement of the vehicle, and signal activating means selectively responsive to the operation of the said electro-magnets and the order of the successive energization of the said circuits.
- 70 75. 12. A signal controlling apparatus having, in combination, a pair of electro-magnets, a circuit for each electro-magnet energized in response to the movement of a vehicle, each electro-magnet controlling the circuit of the other electro-magnet whereby one or the other of said electro-magnets is energized dependent upon the direction of movement of the vehicle, a signal activating means jointly controlled by the selective operation of the said electro-magnets and the subsequent energization of one of said circuits, and means for retaining the said signal activating means effective only when the last mentioned circuit is continuously energized.
- 5 13. A signal controlling apparatus having, in combination, a pair of electro-magnets, a circuit for each electro-magnet energized in response to the movement of a vehicle, each electro-magnet controlling the circuit of the other electro-magnet, whereby one or the other of said electro-magnets is energized dependent upon the direction of movement of the vehicle, and signal activating means jointly controlled by the selective energization of the said electro-magnets and the successive energization of the said circuits.
- 10 15 20 25 30 35 40 45 50 55 60 65 70 75
14. An electrical control for railway signals, comprising, a pair of electro-magnets, a circuit for each electro-magnet energized in response to the movement of a vehicle, each said circuit adapted to energize one or the other of said electro-magnets dependent upon the direction of movement of the vehicle, and means responsive to the energization of either of the said electro-magnets and the successive energization of the said circuits for energizing one or another of a second group of electro-magnets dependent upon the order of the successive energization of the said circuits, and means for retaining the energization of the selected electro-magnet of the first group as long as the selected electro-magnet of the second group is energized.
15. An electrical control for railway signals, comprising, a relay, an operating coil, a circuit for the said operating coil including an armature of the said relay and adapted to be energized in response to a moving vehicle, a second operating coil, and a second circuit for the said second operating coil including an armature operated by the first said operating coil, the said armature of the relay and the first said operating coil, and adapted to be energized in response to the movement of a vehicle.
16. An electrical control for railway signals, comprising, a relay, an operating coil, a circuit for the said operating coil including an armature of the said relay and adapted to be energized in response to a moving vehicle, a second operating coil, a second circuit for the said second operating coil including an armature operated by the first said operating coil, the said armature of the relay and the first said operating coil, and adapted to be energized in response to the movement of a vehicle, and a third circuit adapted to be energized in response to the movement of a vehicle, said third circuit including the armature operated by the first operating coil and an operating coil of the said relay.
17. An electrical control for railway signals, comprising, a relay, an operating coil, a circuit for the said operating coil including an armature of the said relay and adapted to be energized in response to a moving vehicle, a second operating coil, a second circuit for the said second operating coil including an armature operated by the first said operating coil, the said armature of the relay and the first said operating coil, and adapted to be energized in response to the movement of a vehicle, a third circuit adapted to be energized in response to the movement of a vehicle, said third circuit including the armature of the first

operating coil and an operating coil of the said relay, a third operating coil, and a fourth circuit for the said third operating coil adapted to be energized in response to the movement of a vehicle, said fourth circuit including the armature and front contact of the said relay, the armature of the first said operating coil and the operating coil of the said relay.

18. An electrical control for railway signals, comprising, a relay, an operating coil, a circuit for the said operating coil including an armature of the said relay, and adapted to be energized in response to the movement of a vehicle, a second operating coil, a second circuit for the said second operating coil including an armature controlled by the first said operating coil, the said armature of the relay and the first said operating coil, and adapted to be energized in response to the movement of a vehicle, a third circuit adapted to be energized in response to the movement of a vehicle, said third circuit including the armature of the first said operating coil and an operating coil of the said relay, a third operating coil, and a fourth circuit for the said third operating coil adapted to be energized in response to the movement of a vehicle, said fourth circuit including the armature and front contact of the said relay, the armature of the first said operating coil and the operating coil of the said relay, said second and fourth circuits adapted to energize one or the other of the said second and third operating coils dependent upon the selective energization of the said first and third circuits.

19. An electrical control for railway signals, comprising, a track, one of the rails of the said track comprising insulated sections to be bridged by the wheels of a car or train, a plurality of electro-magnets, connections between the said insulated sections and said electro-magnets whereby the wheels of a train engaging the said sections when moving in different directions will energize different electro-magnets, and means responsive to the energization of either of the latter said electro-magnets and the successive engagement of the wheels with the said sections for energizing one or another of a second group of electro-magnets dependent upon the order of the successive engagement of the said sections, and means for retaining the energization of the selected electro-magnet of the first said group as long as the selected electro-magnet of the second group is energized.

20. An electrical control for railway signals, comprising, a track, one of the rails of the said track comprising insulated sections to be bridged by the wheels of a car or train, a plurality of electro-magnets, connections between the said insulated sections and said electro-magnets whereby the wheels of a train engaging the said sections when moving in different directions will energize different electro-magnets, and means responsive to the energization of either of the latter said electro-magnets and the successive engagement of the wheels with the said sections for energizing one or another of a second group of electro-magnets dependent upon the order of the successive engagement of the said sections, and means for retaining the energization of the selected electro-magnet of the second said group only when the wheels of the train maintain a continuous electrical contact during the successive engagement of the said insulated rail sections.

21. An electrical control for railway signals, comprising, a track, one of the rails of the said

track comprising insulated sections to be bridged by the wheels of a car or train, a plurality of electro-magnets, connections between the said insulated sections and said electro-magnets whereby the wheels of a train engaging the said sections when moving in different directions will energize different electro-magnets, and means responsive to the energization of either of the latter said electro-magnets and the successive engagement of the wheels with the said sections for energizing one or another of a second group of electro-magnets dependent upon the order of the successive engagement of the said sections, and means for retaining the energization of the selected electro-magnets of the said first and second groups during the successive engagement of the said sections.

22. An electrical control for railway signals, comprising, a conductor, a pair of contact elements insulated from direct connection with each other and from the said conductor and arranged to be electrically connected to the said conductor by a car or train, a pair of electro-magnets, circuit-connections between the said contact elements and said electro-magnets whereby a train electrically connecting the said elements to the conductor in succession when moving in different directions will energize different electro-magnets, and means responsive to the energization of either of the latter said electro-magnets and the successive electrical connecting of the said elements, for energizing one or another of a second group of electro-magnets dependent upon the order of the successive electrical connecting of the said elements, and means for retaining the energization of the selected electro-magnet of the first said group during the successive connecting of the said elements.

23. An electrical control for railway signals, comprising, a conductor, a pair of contact elements insulated from direct connection with each other and from the said conductor and arranged to be electrically connected to the said conductor by a car or train, a pair of electro-magnets, circuit connections between the said contact elements and said electro-magnets whereby a train electrically connecting the said elements to the conductor in succession when moving in different directions will energize different electro-magnets, and means responsive to the energization of either of the latter said electro-magnets and the successive electrical connecting of the said elements, for energizing one or another of a second group of electro-magnets dependent upon the order of the successive electrical connecting of the said elements, and means for retaining the energization of the selected electro-magnet of the said second group only when the element controlling the energization thereof establishes a continuous electrical connection with the said conductor, and the other of said contact elements is electrically disconnected from the said conductor.

24. An electrical control for signaling systems comprising, a pair of electro-magnets, means for energizing only one of said electro-magnets for one direction of movement of the said vehicle, and the other electro-magnet for the reverse movement of the said vehicle, a second pair of electro-magnets, of means controlled by the said first pair of electro-magnets for selectively connecting one or the other of said second pair of electro-magnets in circuit to be energized in response to the moving vehicle, and means for retaining the energization of the selected electro-

magnet of the said first pair as long as the selected electro-magnet of the second pair is energized.

25. An electrical control for signaling systems comprising, a pair of electro-magnets, means for energizing only one of said electro-magnets for one direction of movement of the said vehicle and the other electro-magnet only for the reverse movement of the said vehicle, a second pair of electro-magnets, of means controlled by the said first pair of electro-magnets for selectively connecting one or the other of said second pair of electro-magnets in circuit to be energized in response to the moving vehicle, and means for retaining the energization of the selected electro-magnet of the said first and second pair effective only as long as the initial energization of the last mentioned electro-magnet continues uninterrupted.

20 26. An electrical control for signaling systems comprising, a pair of electro-magnets, means for energizing only one of said electro-magnets for one direction of movement of the said vehicle, and the other electro-magnet for the reverse movement of the said vehicle, a second pair of

electro-magnets, and means controlled by the said first pair of electro-magnets for selectively connecting one or the other of said second pair of electro-magnets in series with the energized magnet of the first mentioned pair for energization in response to the moving vehicle.

27. An electrical control for signaling systems comprising, a pair of electro-magnets, means for energizing only one of said electro-magnets for one direction of movement of the said vehicle, and the other electro-magnet for the reverse movement of the said vehicle, a second pair of electro-magnets, of means controlled by the said first pair of electro-magnets for selectively connecting one of the said second pair of electro-magnets in series with the said one electro-magnet of the first mentioned pair for energization in response to the vehicle moving in said one direction, and means for connecting the other of said second pair of electro-magnets in series with the said other electro-magnet of the first pair for energization in response to the vehicle moving in the said reverse direction.

FRANK H. RICHTERKESSING. 25
